UNITED STATES PATENT OFFICE.

TRACY RUTLEDGE CAMPBELL, OF MONTREAL, QUEBEC, CANADA.

LOOSE-LEAF BINDER.

Application filed June 30, 1921. Serial No. 481,585.

To all whom it may concern:

Be it known that I, TRACY RUTLEDGE CAMPBELL, a citizen of the United States of America, and resident of Outremont, city 5 of Montreal, in the Province of Quebec and Dominion of Canada, have invented certain new and useful Improvements in Loose-Leaf Binders, of which the following is a specification.

10 This invention relates to improvements in loose leaf binders, of the type having a retaining member formed with posts designed to extend through suitable perforations in the loose leaves and by which they 15 are locked in position, and the objects of the invention are to provide simple and effective means for positioning the loose leaves and retaining them in proper alignment, and generally to improve and 20 simplify the construction of the device and better adapt the various parts to perform the functions required of them.

It consists essentially of the improved construction hereinafter described in detail in 25 the accompanying specification and drawings.

In the drawings:

Figure 1 is a perspective view of an embodiment of the invention.

30 Figure 1^a is a detail, showing a portion of one of the loose leaf sheets.

Figure 2 is a perspective detail of the supporting member.

Figure 3 is a perspective detail of the retaining member.

Figure 4 is an end view.

Figure 5 is a sectional elevation taken through the binding posts.

Figure 6 is a section on the line x-x,

40 Figure 5.

Figure 7 is a sectional elevation of the retaining member.

Figure 8 is a perspective view of the locking member.

45 In the drawings, like characters of reference indicate corresponding parts in all the figures.

Referring to the drawings:

10 and 11 indicate fixed binding posts designed to extend through open slots 12 in the edge of each loose leaf sheet 13, each loose leaf sheet being provided with a plurality of open slots 12 to receive the fixed

posts and a plurality of closed slots or perforations 14 to receive the temporary 55 posts 15 whereby, when the temporary posts are removed, the sheets will be free and may individually be adjusted, removed or replaced, or new sheets added.

In the embodiment illustrated, two permanent posts are provided and three temporary posts, the temporary and permanent posts being arranged alternatively, and the outer and centre posts being temporary posts. All of the temporary posts are connected together and held in spaced parallel relation by means of a retaining member or bar B to which the posts are fixed.

The fixed posts 10 and 11 are held in spaced and parallel relation by a supporting 70 member C of channel shape, preferably formed of a single piece of metal having upper and lower bars or flanges 16 and 17 rigidly connected to the top and bottom of the fixed posts. The back portion 18 of the 75 supporting member C is designed to abut and position the edge of the loose leaves 13, and, it may be pointed out that, in some instances, the posts 10 and 11 might be omitted and the loose leaf sheets positioned 80 by an adjustment against the back portion 18 of the supporting member C. The temporary posts 15 are designed to extend through suitable perforations 19 in the bars 16 and 17.

85 The retaining member B is designed to be held in engaged position by spring released retaining means; the spring releasing means which I have designed comprising a flat spring 20 secured beneath the member 90 B and centrally thereof, and having its outer end turned downwardly slightly and adapted to bear against the bar 16 whereby the spring will tend to place the supporting member a short distance above the bar 16, 95 and the turning of the spring about the central posts being prevented by means of rivets 21 on opposite sides of the post.

The retaining member is held in engaged position by a longitudinally slid able locking bar D having slots 22 through which the temporary posts extend, the edge of the slots being adapted to engage and lock at notches 23 in the temporary posts, the edge of the slots being held in engagement with 100 the posts by a spring 24 extending from one

end of the locking bar D to the end of the bar 16. The locking bar is also formed with slots 25 through which the permanent posts 10 and 11 may extend.

5. The locking bar D may be retained in position against the bar 16 in any convenient way. I have shown it positioned on the underside of the bar in a channel formed by a retaining bar 26 which is spaced a short distance from the underside of the bar 16 and suitably connected thereto. The bar D may be formed with a slot 27 at one end through which a connecting rivet 28 between the bars 16 and 26 may extend. The end of the locking bar D is preferably formed with a downwardly turned projection 29 by means of which it may be readily engaged.

10 The supporting member C is preferably incorporated as part of a book, the back 30 of the book being connected to the back 18 of the supporting member, and the covers 31 and 32 being designed to lie parallel with the bars 16 and 17. The cover 32 is formed with a flexible portion 33 designed to extend over the retaining member B whereby there will be no protruding parts on the exterior of the book.

15 It will be seen from the foregoing that, when the parts are assembled as shown in Figure 1, the retaining member B may be released by longitudinal movement of the bar D; upon being released will spring upwardly by action of the spring 20, when it may be grasped and removed. When removed, the sheets 13 will all be free, and may be adjusted, removed, or added to, if desired. To lock the sheets in position, the retaining member is returned to position, the lower ends of the temporary posts being 20 pointed to facilitate their insertion, and the locking bar D springing into locking position as soon as the notches 23 pass beneath the bar 16.

25 As many changes could be made in the above construction and many apparently widely different embodiments of my invention within the scope of the claims, constructed without departing from the spirit or scope thereof, it is intended that all matter contained in the accompanying specification and drawings shall be interpreted as illustrative and not in a limiting sense.

30 What I claim as my invention is:

1. In a binder, a supporting member comprising a single piece of channel metal formed with upper and lower flanges, a retaining member having temporary posts extending through the flanges, and a flat spring on the underside of the retaining member adapted to normally retain it in position a short distance removed from one of the flanges, and locking means adapted to hold the retaining member in engaged position.

2. In a binder, a supporting member comprising a single piece of channel metal formed with upper and lower flanges, a retaining member having temporary posts extending through the flanges, a flat spring on the underside of the retaining member adapted to normally retain it in position a short distance removed from one of the flanges, a longitudinally slideable bar adapted to lock the retaining member against the action of the spring, and a supporting bar designed to maintain the longitudinally slideable bar in position.

3. In a binder and in combination, a non-distensible supporting member formed from a single piece of channel metal formed with parallel upper and lower flanges and with a back portion, permanent posts connecting the flanges, a retaining member having temporary posts extending through the flanges, manually releasable means for holding the retaining member in engaged position, and a cover formed with a flexible portion extending over the retaining member to the supporting member.

4. In a binder and in combination, a non-distensible supporting member formed from a single piece of channel metal formed with parallel upper and lower flanges and with a back portion, permanent posts connecting the flanges, a retaining member having temporary posts extending through the flanges, and manually releasable means for holding the retaining member in engaged position.

5. In a binder, a supporting member, comprising a single piece of channel metal formed with upper and lower flanges, a retaining member having temporary posts extending through the flanges, spring means on the underside of the retaining member adapted to normally retain it in a position a short distance removed from one of the flanges, a slideable locking bar mounted on one of the flanges adapted to engage and lock against one of the temporary posts.

6. In a binder, a binder comprising a solid non-distensible supporting member formed with upper and lower flanges, and with a back portion, permanent posts connecting and bracing the flanges, and adapted to form a guide against which the sheets in the book may be adjusted, a retaining member arranged on the outside of the supporting member having temporary posts extending through one of the flanges, and adapted to lock the sheets in position in the binder, and manually releasable means for holding the retaining member in engaged position.

7. In a binder, a binder comprising a solid non-distensible supporting member formed with upper and lower flanges, and with a back portion, permanent posts connecting and bracing the flanges, and adapted to form a guide against which the sheets in

the book may be adjusted, a retaining member arranged on the outside of the supporting member having temporary posts extending through one of the flanges, and adapted to lock the sheets in position in the binder, and manually releasable means for holding the retaining member in engaged position, and spring means extending between the

retaining member and the supporting member.

In witness whereof I have hereunto set my hand in the presence of two witnesses.

TRACY RUTLEDGE CAMPBELL.

Witnesses:

LEE AUGUST JOHNSON,

WILLIAM MOORE WOODARD.
